UNITED STATES PATENT OFFICE.

ALEXIS R. PRIBIL, OF DETROIT, MICHIGAN, ASSIGNOR TO PENBERTHY INJECTOR CO.,
OF DETROIT, MICHIGAN, A CORPORATION OF MICHIGAN.

LUBRICATOR.

1,032,502.

Specification of Letters Patent. Patented July 16, 1912.

Application filed May 15, 1911. Serial No. 627,207.

To all whom it may concern:

Be it known that I, ALEXIS R. PRIBIL, a citizen of the United States of America, residing at Detroit, in the county of Wayne 5 and State of Michigan, have invented certain new and useful Improvements in Lubricators, of which the following is a specification, reference being had therein to the accompanying drawings.

10 This invention relates to a gravity feed lubricator more specifically designed for lubricating the cylinder of explosive engines. In the construction of such lubricators it is necessary to provide a check valve in the 15 outlet from the sight chamber and to this end a ball valve is usually placed in the discharge outlet from the sight chamber to check the inrush of the gases into said chamber while the explosion is taking place. 20 As the gases at the time of the explosion are under very high pressure the small portion thereof which is permitted to pass around the ball valve into the sight chamber for the purpose of equalizing the pressure in the 25 lubricator not only interferes with the formation of the drop but the fine sooty particles of carbon and smoke accompanying the exploded charge in time coats the inner wall of the glass tube of the sight chamber 30 and makes observation impossible.

It is the object of this invention to provide a construction which overcomes the trouble arising from the above mentioned cause and the invention consists to this end 35 in the novel construction and arrangement of a ball-valve all as hereinafter described and shown in the accompanying drawings, in which—

Figure 1 is a vertical central section of a 40 lubricator embodying my invention in its preferred form; Fig. 2 is a part of the discharge arm thereof on an enlarged scale; Fig. 3 is a horizontal section on line 3—3 of Fig. 2; and Fig. 4 is a horizontal section on line 4—4 of Fig. 2.

45 Referring to the drawings, 1 is a shell forming in connection with the heads 2 and 3 the oil cup, the shell being clamped between the heads by means of a vertical hollow post 4 integrally cast with the bottom head and passing through an aperture in the top head, the projecting end being screw-threaded and provided with a clamping nut 5. The top of the hollow post bears 50 a notched screw cap 6 held against accidental

turning by a leaf spring 7 fastened in position upon the post by the clamping nut 5. Within the hollow post is a valve stem 8 terminating at its lower end in a tapering valve 9 and bearing at its upper end the snap handle 10 pivoted thereto whose flattened lower end rests upon the cap 6 and serves to operate the stem 8 vertically to open or close the valve, a coil spring 11 being interposed between the cap 6 and a shoulder 12 formed on the valve stem. The lower head is formed with a valve seat for the valve 9 and with a discharge nipple 13 into the sight chamber below and communicating with the interior of the cup through apertures 14 in the post. The sight chamber is formed of a glass tube 15 inclosed in a cylindrical shell 16 integrally cast with the lower head and provided with the usual sight openings. In the lower end of this housing is secured a screw plug 17 which clamps the glass tube in position and forms in connection with the shell 16 the discharge arm of the cup. The screw plug terminates in a screwthreaded nipple 18 for attaching the lubricator to the part to be lubricated, it is formed with an expansion chamber 19 the bottom of which is conically depressed and provided with a final outlet 20. The top of this chamber is formed by a screw plug 21 which is provided with a nipple 24 projecting into the expansion chamber to near the final outlet and inclosing the usual ball valve 25. The sight chamber is provided with an outlet 23 through this nipple 24 in which the ball valve is guided in its movement between a seat 26 formed in this outlet and a seat 27 formed on the final outlet 20. To prevent the ball from wholly obstructing the final outlet the latter is given 95 a polygonal cross section, the seat 27 being formed within the area of the cross section as shown in Figs. 3 and 4.

The ball valve when seated upon the final outlet prevents the oil from feeding freely 100 into the chamber 19 since its upper half projects into the lower end of the nipple and causes the formation of an oil seal between the same which while it does not interfere with the proper operation of the device 105 makes the ball valve very sensitive so that even at the slightest inrush of burnt gases into the chamber 19 the ball will quickly seat itself in the nipple against the seat 26 with the oil seal remaining practically un- 110

broken. Any diffusion or inrush of burnt gases with the accompanying smoke particles into the sight chamber is thus prevented.

5 While I have described my lubricator with sole reference to its application for explosive engines, it is quite obvious that it may be equally used in connection with air compressors or the like.

10 What I claim as my invention is:—

In an explosion engine lubricator, a discharge arm having a sight chamber provided with an outlet at the bottom and with an expansion chamber below the sight 15 chamber, having a final outlet at its bottom,

a ball valve in the expansion chamber movable between the two outlets, each outlet provided with a seat for the ball valve and a nipple depending from the bottom of the sight chamber around the outlet therefrom 20 into the expansion chamber and adapted to form in connection with the ball valve an oil seal between the two chambers.

In testimony whereof I affix my signature in presence of two witnesses:

ALEXIS R. PRIBIL.
